UNITED STATES PATENT OFFICE.

LOUIS RUBENSTEIN, OF ALEXANDRIA, LOUISIANA.

DESIGN FOR A PARTY-BOX.

46,887.

Specification for Design.

Patented Jan. 26, 1915.

Application filed October 14, 1914. Serial No. 866,713. Term of patent 3½ years.

To all whom it may concern:

Be it known that I, LOUIS RUBENSTEIN, a citizen of the United States, residing at Alexandria, in the parish of Rapides and State of Louisiana, have invented a new, original, and ornamental Design for a Party-Box, of which the following is a specification, reference being had to the accompanying drawing, forming part thereof.

The figure is a view in perspective.

I claim:

The ornamental design for a party box as shown.

In witness whereof, I have hereunto subscribed my name in the presence of two witnesses this 5th day of October 1914.

LOUIS RUBENSTEIN.

Witnesses:

LILLIAN E. CHRISTIANSON,
MARCUS A. HIRSCHL.
